(57) **CLAIM**

The ornamental design for a lawn mower, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a lawn mower showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a bottom, front perspective view thereof; and,

FIG. 8 is a left, top perspective view thereof.

The portions of the lawn mower shown in light gray areas in FIG. 2 form no part of the claimed design.
